UNITED STATES PATENT OFFICE.

CHARLES T. WESTLAKE, OF ST. LOUIS, MISSOURI, ASSIGNOR TO DAVIS LOCOMOTIVE WHEEL COMPANY, OF ST. LOUIS, MISSOURI, A CORPORATION OF DELAWARE.

METHOD OF COUNTERBALANCING CRANK-WHEELS.

No. 823,750.

Specification of Letters Patent.

Patented June 19, 1906.

Application filed February 12, 1906. Serial No. 300,820.

To all whom it may concern:

Be it known that I, CHARLES T. WESTLAKE, a citizen of the United States, residing at St. Louis, in the State of Missouri, have invented 5
5. a new and Improved Method of Counterbalancing Crank-Wheels, of which the following is a specification.

My invention relates to an improved method of counterbalancing the weight of the 10 crank-pin and its appurtenances in a crank-wheel, and has for its object to obtain a perfect equilibrium of the wheel when so loaded during a complete revolution thereof on its axle in every position of the crank-pin.

15 According to the usual method of counterbalancing a crank-wheel when free to revolve on its axle and formed with a counterbalance-weight approximately equal to, but invariably, owing to inequality of casting, either 20 greater or less than that required, a pin or bolt is temporarily fixed centrally in the crank-pin hole, and from the outer projecting portion of the pin is suspended the actual weight of the crank-pin and its appurtenances. 25 A similar pin is then fixed to the spokes of the wheel adjacent to its counterbalance-weight and at a point diametrically opposite to the crank-pin, and from this pin or from that at the crank-pin hole (as the case may be) is 30 suspended additional weight until the wheel balances. The amount of weight to be added to or subtracted from the counterbalance-weight can then be mathematically ascertained. If the weight is to be deducted from 35 the counterbalance, the face of the latter is reduced by planing, and if to be added thereto sheet metal of the requisite weight and cut to the outline of the counterbalance is riveted thereon. When the crank-wheel is provided with two counterweights, this method 40 is complex and unreliable.

My invention consists in features of novelty, as hereinafter described and claimed, reference being had to the accompanying 45 drawings, forming part of this specification, whereon—

50 Figure 1 is an inner side elevation of a locomotive crank-driving wheel constructed according to my invention; Fig. 2, a cross-section thereof on line 2 2 in Fig. 1, and Fig. 3 an edge view to reduced scale of the wheel, (broken away,) showing the method of deter-

mining the counterbalance-weight required therefor.

Like letters and numerals of reference denote like parts in all the figures.

a represents a crank - wheel having the crank-arm *b*, in which is formed the hole 1 for the crank-pin (not shown) in the usual well-known manner. For counterbalancing the 60 combined weight of the crank-arm *b* and its loaded crank-pin the wheel *a* is formed or provided, preferably near its circumference, at an equal distance radially from the arm *b* and from each other, with preferably two 65 counterbalance-weights *c* of equal weight, their aggregate weight being somewhat less than that of the arm *b* and its appurtenances. Transversely through (or part way through) each counterbalance *c* and parallel to the 70 axis of the wheel *a* is formed a circular hole 2, which is described from a center line intersecting the center of gravity of the counterbalance *c*, and about the hole 2, at equal distances, respectively, from each side of a radial line passing through the center of the hole 2 and through the axial center of the wheel *a*, 75 are formed, preferably in its inner side and part way through the counterbalance *c*, one or more circular recesses or holes 3, which are 80 parallel to the hole 2 and symmetrically arranged relatively thereto and to each other.

For determining the amount of extra weight to be added to each counterbalance *c* for balancing the crank-arm 1 and its appurtenances the wheel *a* is mounted and free to revolve on its axis *d*. (See Fig. 3.) A temporary pin or bolt 4 is then fixed in and projects centrally from the crank-pin hole 1, and from the pin 4 is suspended a weight 5, equal to that of the said parts to be balanced. A similar pin or bolt 6 is fixed in the hole 2 of each counterbalance *c*, and from the pins 6 are suspended equal weights 7, which are adjusted, respectively, until they are exactly 90 equal in the aggregate to the weight 5 on the pin 4 or the wheel *a* balanced.

Now as a weight falls as though its particles were concentrated at its center of gravity and as the holes 2 and 3 are arranged 100 symmetrically about the center of gravity of each counterbalance *c*, any weight added to the latter by filling or partly filling the holes 3 uniformly on each side of the hole 2 will act

as though concentrated at the center of gravity of the counterbalance *c*, or, in other words, on removing the temporary pins 4 and 6 with the weights 5 and 7 from the wheel *a* and 5 then filling or partly filling the holes 3 of each counterbalance *c* in the order described with an aggregate weight of metal equal to that of its test weight 7 the wheel *a* will be accurately balanced in whatever position the 10 crank-arm *b* and its appurtenances may be during a complete revolution of the wheel *a* on its axis *d*.

The advantage of my improved method over the ordinary method is the facility with 15 which the adjustment is effected in adding to the counterbalance by filling the holes 3 instead of by riveting plates thereto. Also by applying the test weight at the center of gravity of the counterbalance the necessity 20 of calculating the required weight is obviated and the result obtained consequently more accurate and reliable.

What I claim as my invention, and desire to secure by Letters Patent, is—
25 The method of balancing a crank-wheel,

consisting in forming the counterbalance thereof initially of less weight than that of the parts to be balanced, forming a hole in the counterbalance at its center of gravity parallel to the axis of the said wheel, forming a 30 recess in the counterbalance at each side of a radial line passing through the centers of the said axis and hole, the said recesses being symmetrically arranged relatively to the said hole and to each other, determining the extra 35 weight to be added to the counterbalance by suspending weights respectively from the crank-wheel at the center of its crank-pin hole, and from the counterbalance at its center of gravity, and inserting the proportionate part of the said weight within each of the said recesses, substantially as described.

In testimony whereof I have signed my name to this specification in the presence of two subscribing witnesses.

CHARLES T. WESTLAKE.
